UNITED STATES PATENT OFFICE

EARL E. EICKMEYER, OF DAYTON, OHIO, ASSIGNOR TO THE DAYTON PUMP & MFG. COMPANY, OF DAYTON, OHIO, A CORPORATION OF OHIO

GASOLINE PUMP

Application filed October 31, 1928. Serial No. 316,246.

My invention relates to gasoline pumps.

It is the object of my invention to provide a gasoline dispensing pump in which it is impossible to move the handle, which sets the quantity of gasoline to be dispensed, while the dispensing operation is taking place.

It is a further object to provide a pump in which the valve controlling the delivery of gasoline from the visible container to the automobile is locked against being opened until the handle of the setting mechanism is in operative set position.

It is a further object of my invention to provide means of limiting the upward and downward movement of the measuring tube.

It is a further object to provide a single unitary manifold for use in connection with a measuring tube which is operated by the setting mechanism and the overflow so that no more than a predetermined quantity of gasoline can be delivered to the visible container.

It is a further object of my invention to provide an interlocking system so that, when the setting mechanism for setting the delivery of a given quantity of gas is placed in the draining position, it will then be possible to place the delivery hose in the drain-back passageway and, when the hose is locked in such passageway, the action of locking will simultaneously unlock the drain valve in the hose which, up to that time, has been locked against movement.

It is a further object to provide for unlocking the mechanism which has locked the hose lock in inoperative condition, such unlocking of the lock taking place by the passing of the setting rack into its lowermost position.

It is a further object of my invention to provide a sight drain in the delivery line from the visible container to an automobile so that all of the gasoline passing through the pipe can be seen.

It is an additional object to provide a stop interposed between the supply pipe and the locking pin on the setting mechanism so as to prevent the operation of the lock when it is in set position.

It is a further object to provide a unitary pump so arranged that the pumping mech-

anism is carried on the cast iron base and the setting mechanism, together with the sump casting and the bowl of the visible container, are all carried on a supplementary structure mounted upon the base but independent of the pump, while the casing for the pump is purely a casing without any structural function. 55

Referring to the drawings:

35 Figure 25 is a detail view of the pump mechanism and the drain back in unlocked position;

40 Figure 26 is a detail view broken away to show the calibration adjustments of the numeral plate;

45 Figure 27 is a section through the sump casting and drain back showing the detail and method of maintaining a tight joint between the adjusted rod for the drain tube and the sump; and

50 Figure 28 is a detail side elevation of the upper portion of the pump.

45 Referring to the drawings in detail, 1 is a base upon which is mounted conventional pumping mechanism of any desired character designated 2 operated by the segment 3 from the handle 4 which in turn operates the 55 rack 5. Gasoline from an underground container is pumped up through the supply pipe 6 by this pump.

55 This supply pipe terminates at its upper end adjacent the bottom 7 which carries the 60 visible bowl of glass designated 8. A unitary casting containing a sump is provided with a sleeve 9 and a gasket 10 for accommodating the upper end of the supply pipe 6. The gasket 10 is held yieldingly in place by the 65 gasket follower 11 which is spring pressed by the springs 12 suspended on the pins 13 that are carried on the sleeve 9.

65 A second supply pipe 14 is threaded into this casting 9 and extends into the visible bowl 8. It delivers the gasoline over the top

of this pipe 14 beneath a spaced dome 15 carried thereby.

70 Gallon indicators 16 are mounted upon a supporting rod 17 within the bowl 8, the lower ends of the rods 17 being mounted upon the floor 7 of the bowl and carried from the top 18 thereof. This top 18 is provided with a glass window 19 so that the electric lamp may illuminate the interior of the bowl 8. The electric lamp is designated 20.

75 As will be seen in Figures 9 and 27 the sump casting is provided with a chamber 21 in which slides a measuring tube 22 that may be moved into position in the glass bowl 8 according to the measurement desired so that

80 the gasoline, the height of which is indicated by the height of the tube 22, may be measured and flow from a bowl 8 upon the lowering of the tube 22 to the position shown in Figure 27. This tube 22 is mounted upon

85 a rod 23 known as the measuring rod. It is connected by a spider 24 to the tube 22 so that the gasoline can flow back through the measuring tube around the spider into the chamber 22 in which the measuring tube telescopes.

90 The spider 24 is formed on the lower end of the tube 22 by forming therein, on each side, a slit 22a. The parts of the walls between this slit and the lower end of the tube are pressed in, as shown in Figure 8, to form the parts of the spider. The inner parts of the pressed-in walls engage the rod 23 and are fastened thereto by rivets, or any other suitable means.

95 The gasoline flows down through the bottom of the tube 22, thence upwardly through the tapered passageway 25 whence it passes over into the horizontal passageway 26 into the delivery pipe 27 through the sight flow glass 28 past the hose drain valve 29 and into the hose 30. Also connected to this sump

100 casting is the overflow tube 31 which is so arranged that any gasoline in excess of the total quantity which can be safely placed in the container will drain back into the reservoir below the pump. This pipe 31 therefore is mounted in the upper end of the casting at the point indicated at 32 so that the gasoline flowing back through it will pass down

105 through semi-circular passageway 33 to the bottom of the casting and thence in a semi-circular path through the passageway 34 into the drain back pipe 36, all as indicated by the arrows.

110 The bottom of the sump 25 is also provided with a sump drain 37 for independent drainage.

115 38 is an air inlet line that communicates with the passageway 26 and with the bowl 8.

120 The sump casting is attached to the bottom 7 of the bowl by the bolts 39. The bowl itself is provided with a cover 40 which is adapted to carry in the rim 41 a suitable glass device for advertising purposes, which is not illustrated, as it forms no part of this invention.

The base 42 which supports the bottom 7 of the visible bowl is, in turn, supported by three spaced frame rods 43 which are bolted to the top of the base 1.

5 *Setting mechanism*

The setting mechanism consists of a disc or circular plate 44 having a plurality of apertures 45, designated by numerals indicating gallons which can be secured by placing the setting handle 46 opposite thereto and inserting the setting pin 47 in the proper aperture 45. The pin 47 is pivoted by means of a yoke 48 to a pin 49 in the handle 46. The inner end of the pin 47 is tapered, as at 50, so that it will easily and readily enter the apertures 45 in the plate or disc 44, and also so it will engage and easily pass by the adjustable jaws 54. Beneath the apertures 45 there are 10 slots 51 in an annular numeral plate 52, as shown in Figure 26. There is provided a housing or drum 53 for containing the apparatus for obtaining a fine adjustment so that the exact proper amount of gasoline will 15 be delivered to the globe or bulb located at the top of the tank. Within this drum is a plurality of jaws 54 pivoted by means of screws 55 to the drum. There is one set of jaws for 20 each aperture 45 in the plate 44.

25 Extending from each pair of jaws and integral therewith is an arm 56, which has provided therein a screw-threaded opening to receive a screw 57. The inner end of this screw is headed and abuts the head of a similar screw 57a screwed into a hub 58 located in the center of the drum or housing. The lever or handle 46 is pivoted by means of ears 59 to one end of an oscillating plate 59a. Extending from the other end of the plate 40 59a is a tubular support 60 which fits into a bearing sleeve 61. On the free end 62 of the handle there is a pivot pin 63 which engages a yoke 64 on the upper end of a locking pin 65.

45 When any particular number of gallons of gasoline is desired the pin 47 is inserted into the aperture 45 opposite the number of gallons desired on the number plate. When this pin is thus inserted, as shown in Figure 14, 50 the locking pin is withdrawn so that the mechanism may be operated for opening the valve to deliver gasoline to the purchaser. During the time that the pin 47 is withdrawn from the apertures 45 the locking pin 65 is 55 inserted inward to its full extent so that no delivery of gasoline can be effected.

In order to effect a fine adjustment the screw 57 may be rotated to adjust the jaws 54 to properly position the handle when the 60 pin 47 is inserted between the jaws 54. Thus adjustment is effected by the rotation of the screw 57. This screw is in adjusted position between the outer walls of the drum and the hub 58. The locking pin is provided with locking notches 66 in which rides a spring 65

pressed plunger 67 carried in the sleeve 68 which is mounted upon the tubular bearing sleeve 61. Thus, when the setting handle 46 is in measuring position the locking pin 65 will be in unlocked position, while the setting pin 47 will be in operative position. At this time, the stop 69 will be between the supply tube 6 and the end of the locking pin 65. This stop is carried upon the rod.

The tubular sleeve 60 carries on its inner end the setting gear 70 which meshes with the rack 71 guided in the rack way 72. This rack is connected at its lower end by a bracket 73 to the measuring rod 23 so that the movement of the setting handle 46 will position 75 the setting rod.

The bracket 73 is arranged to receive the stationary rod 74 on which is mounted a spring 75 at the bottom thereof on the washer 76. The upper end of this spring is engaged 80 by a sleeve 77 slidably mounted on the rod 74. The sleeve carries a stud 78 which is engaged by the bottom of the bracket 74 when it descends with the adjustment rack in order to compress the spring 75 and lower the locking member 79 out of the path of the locking pawl 80 which is connected at one end to the hose valve rod 81 and pivoted at the other end at 82 to the lower end of the bracket 73.

The function of this mechanism in connection with the locking of the hose drain for the night and the placing of the operating handle in draining position will be described hereinafter.

100 *Hose drain valve control*

The hose drain valve 29 is controlled by the rotating shaft 83 and 84 from which are suspended the weighted operating handle 85. The inner end of the shaft 84 is provided 105 with an arm 86 extending laterally therefrom. This arm 86 is pivotally connected at 87 to the depending rod 88 that is pivotally connected at 89 to the reciprocating locking block 69 that is adapted to be interposed between the filler pipe 6 and the end of the locking pin 65 when the valve is open and the spring 90 is compressed. The spring 90 is between the locking block 69 and the stationary bracket 91 through which projects 110 the guiding rod 74 around which the spring 90 is mounted and on which the locking block 69 slides.

When the hose valve is in locked position the spring 90 is expanded, as in Figure 18, the locking block is up and the locking pin 65 is extended into the casing of the pump beneath the locking block 69 so that the hose valve cannot be operated as the operating handle is not in setting position for the operation of the pump and discharge of gasoline.

120 *Hose drain locking mechanism*

The drain line 36 is connected in the line 125 by a fitting 92 of T-shape, the lateral portion

of which 93 is connected to a laterally and upwardly extending hose receiving fitting 94. The fitting 92 is provided with a gate valve 95 which is adapted to be opened by the movement of gasoline through the pipe 94 into the pipe 36.

This pipe 94 is provided with a shouldered collar 96 threaded on its upper end with a recessed mouth to receive a washer 97 against 10 which the shoulder 98 of the nozzle 99 on the hose 30 rests. The nozzle 99 approaches into the pipe 94. A laterally-extending flange on this nozzle designated 100 is engaged by the set screws 101 carried in the swinging clamping lever 102 which is pivoted on the pivot 103 upon a bracket 104 of the collar 96.

Also pivoted on this collar is the rod 82 that carries at one end the movable locking finger 80. This rod 82, which is pivotally mounted for the movable locking finger 80, is journaled in the collar 96 and carries on its other end the locking lever 105 which is provided with an eye 106 for receiving the hasp of a lock which is also inserted within 25 the eye 107 on the clamping lever 102.

A pivoted door is provided for closing the pipe 94 when the hose is in operation supplying gasoline to automobiles. This door is designated 108 and is hinged at 109 on ears 30 110 which are formed as a part of the collar 96. This hinged door cover 108 is provided with a tapered shoulder 111 so that the set screws 101 can engage the top thereof for holding the door adjustably closed, over the 35 open end of the pipe 94. The lock which passes through the eyes 106 and 107 is designated 112.

Sight flow on the hose drain

40 The peculiar construction of the hose drain will be noted. All the gasoline flowing can be seen as the bottom of the glass through which the gasoline is passing is visible and is not covered up by a metallic casing as hitherto has been the case. This glass is designated 28.

By offsetting the threaded sleeve 113 below the center line of the glass 28 which is held 50 within the housing 114 it is possible for the gasoline to pass from the pipe 27 into the pipe which forms a part of the valve 29 and be compelled to bore through the glass 28 as the pipe 29 is lower than the glass 28. 55 The housing 114 supporting the glass 28 is cutaway at 115 to a point below the bottom of the glass 28.

The operating mechanism is enclosed by a cover 116. The gasket 117 around the 60 measuring tube rod 23 is held in position by the gasket retainer 118 which in turn is held in yielding position by the springs 119 carried on the bolts 120 that are suspended from the bottom of the manifold casing and passed 65 through the gasket retainer 118.

Method of operation

In operating this pump the visible container 8 is first filled by the operation of the pump 2 through the handle 4. This supplies 70 gasoline from the underground tank through the pipe casing 9, pipe 14 to the bowl.

The bowl now being full and the valve 29 closed, it is impossible to open the valve 29 as the operating handle has not been put in any setting position with the result that the locking pin 65 extends below the member 69 so that 69 cannot be lowered which is necessary to open the hose valve 29 as the rod 88 interconnects the member 69 and the valve 29. 80

The operating handle 46 is moved to the number of gallons desired, the pin 47 is inserted in the hole opposite the number of gallons desired. This withdraws the locking pin 65 and then the handle 85 can be pushed up against the resistance of the spring 90 lowering the member 69 and allowing the gasoline to flow to the extent that the measuring tube 22 has been lowered by the rotation of the setting handle 46, its gear 70 and the rack 71 which are interconnected with the tube 22 by the rod 23 which is connected thereto through the medium of the bracket 73. 90

The gasoline makes its exit through the manifold hereinbefore described on its way to the pipe 27, sight glass 28, valve 29 and hose 30. 95

Thus, it is impossible for the operator to hit the handle 46 with his hand and change the adjustment of it after the operation is once started which is a common defect of present pumps, and results in the stealing of a large amount of gasoline daily at busy gasoline stations where the customer does not perceive this trick on the part of the operator of the pump. The interlocking connection between the setting mechanism and the hose drain valve prevents any tampering with the adjustment after it is once made and the operation started. 100

At night, when it is desired to drain the bowl 8, the setting handle is moved to the draining position and the pin 47 is inserted in the drain hole. This results in withdrawing the locking pin 65. It also results in running the rack down to its lowermost position with the consequence that the bracket 73 engages the pin 78, compresses the spring 75 by depressing the collar 77 and the locking lug 79. This frees the locking finger 80 and permits it to rotate with the shaft 82 which is operated by the movement of the handle 105 upwardly into operating position where the lock can be inserted through the eyes 106 and 107. In the meanwhile, the nozzle 99 has been inserted in the pipe 94 and the clamping lever has been put in position to clamp it in engagement with the pipe 94. 110

When the lever 105 is thus elevated it pulls down upon the rod 81 which in turn pulls on the lever 86 through which it is inserted loose- 115 120 125 130

ly and this rotates the rod 84, lifts the handle 85 and opens the valve 29 so that the gasoline will flow out of the bowl through the hose, the pipe 94, the pipe 36 back into the reservoir. This drain position will be locked by the lock. It will be impossible thereafter to operate the setting mechanism and the remainder of the apparatus. Any pumping of gasoline from the main tank will merely result in it running back immediately into the hose and thence back into the main tank.

It will be understood that I desire to comprehend within my invention such modifications as may be necessary to adapt it to varying conditions and uses.

Having thus fully described my invention, what I claim as new and desire to secure by Letters Patent, is:

1. In a gasoline dispensing pump, the combination of a pump, a measuring bowl, a delivery hose, a delivery valve in said hose and measuring mechanism for determining the exact amount of gasoline from out of the measuring bowl through the hose, locking means associated with said measuring means so arranged that the hose valve cannot be operated until the measuring means is positioned into operative position, a drain back to the original source of supply adapted to receive the free end of the hose, means for locking said hose in said drain back, means for locking said hose locking means in inoperative condition while the measuring means is in positions other than the drain position, and means upon setting the measuring means at draining position for permitting the locking of the hose in the drain back.

2. In a gasoline dispensing pump, the combination of a pump, a measuring bowl, a delivery hose, a delivery valve in said hose, measuring mechanism for determining the exact amount of gasoline drawn from the measuring bowl through the hose, locking means associated with said measuring means so arranged that the hose valve cannot be operated until the measuring means is positioned into operative position, a drain back to the original source of supply adapted to receive the free end of the hose, means for locking said hose in said drain back, means for locking said hose locking means in inoperative condition while the measuring means is in positions other than the drain position, and means upon setting the measuring means at draining position for permitting the locking of the hose in the drain back, and interconnecting means between the hose drain back, locking means and the hose valve whereby the valve is opened upon the locking of the hose in the drain back.

3. In a gasoline filling station pump, the combination of a measuring bowl, adjustable measuring means, a delivery hose connected to said bowl, a valve in said hose, interlocking means between said valve and said meas-

uring means to prevent the operation of the valve until the measuring means is placed in adjusted position, a drain back, means to lock the free end of the hose in the drain back, said locking means being interconnected with said hose valve to open it when the hose is locked in the drain back.

4. In a gasoline filling station pump, the combination of a measuring bowl, adjustable measuring means, a delivery hose connected to said bowl, a valve in said hose, interlocking means between said valve and said measuring means to prevent the operation of the valve until the measuring means is placed in adjusted position, a drain back, means to lock the free end of the hose in the drain back, said locking means being interconnected with said hose valve to open it when the hose is locked in the drain back, and means associated with the measuring means for preventing the operation of the hose drain back lock until the measuring means is placed in drain back position.

5. In a gasoline filling station pump, the combination of a measuring bowl, adjustable measuring means, a delivery hose connected to said bowl, a valve in said hose, interlocking means between said valve and said measuring means to prevent the operation of the valve until the measuring means is placed in adjusted position, a drain back, means to lock the free end of the hose in the drain back, said locking means being interconnected with said hose valve to open it when the hose is locked in the drain back, and means associated with said measuring means to prevent its accidental operation into any other delivery adjustment until the measuring operation has been accomplished.

6. In a gasoline filling station pump, the combination of a measuring bowl, adjustable measuring means, a delivery hose connected to said bowl, a valve in said hose, interlocking means between said valve and said measuring means to prevent the operation of the valve until the measuring means is placed in adjusted position, a drain back, means to lock the free end of the hose in the drain back, said locking means being interconnected with said hose valve to open it when the hose is locked in the drain back, and means associated with the measuring means for preventing the incidental operation of the hose drain back lock until the measuring means is placed in drain back position, and means associated with said measuring means to prevent its operation into any other measuring adjustment until the delivery operation has been accomplished.

7. In combination in a gasoline dispensing pump, a hose drain valve, a locking member connected thereto for locking a setting mechanism against movement when the valve is opened, a setting mechanism, a locking mechanism therefor adapted to prevent the

opening of the valve while the setting mechanism is in inoperative position or is being moved to a set position, and a supply pipe adapted to act as an abutment for supporting the valve lock when it operates to prevent the movement of the setting mechanism lock.

8. In combination in a gasoline dispensing pump, a hose valve, a lock connected thereto, yielding means for maintaining said lock and valve in inoperative closed position, setting mechanism comprising a setting crank, gear mechanism operated thereby, a setting lever pivotally mounted on said crank, a locking pin reciprocating through said crank and gear mechanism adapted to project alternately through either end thereof connected to one end of said setting lever, a setting pin connected pivotally to said setting lever on the other side of its pivotal mounting on the crank, a setting drum having a plurality of apertures for receiving said setting pin, said locking pin and valve lock being adapted to lock one another whereby when the setting mechanism is in operative position the valve cannot be opened and when the valve is opened the setting mechanism cannot be moved.

9. In combination in a gasoline dispensing pump, a hose valve, a lock connected thereto, yielding means for maintaining said lock and valve in inoperative closed position, setting mechanism comprising a setting crank, gear mechanism operated thereby, a setting lever pivotally mounted on said crank, a locking pin reciprocating through said crank and gear mechanism adapted to project alternately through either end thereof connected to one end of said setting lever, a setting pin connected pivotally to said setting lever on the other side of its pivotal mounting on the crank, a setting drum having a plurality of apertures for receiving said setting pin, said locking pin and valve lock being adapted to lock one another whereby when the setting mechanism is in operative position the valve cannot be opened and when the valve is opened the setting mechanism cannot be moved, and yielding positioning means for positioning the setting mechanism lock.

10. In combination in a gasoline dispensing pump, a hose valve, a lock connected thereto, yielding means for maintaining said lock and valve in inoperative closed position, setting mechanism comprising a setting crank, gear mechanism operated thereby, a setting lever pivotally mounted on said crank, a locking pin reciprocating through said crank and gear mechanism adapted to project alternately through either end thereof connected to one end of said setting lever, a setting pin connected pivotally to said setting lever on the other side of its pivotal mounting on the crank, a setting drum having a plurality of apertures for receiving said setting pin, said locking pin and valve

lock being adapted to lock one another whereby when the setting mechanism is in operative position the valve cannot be opened and when the valve is opened the setting mechanism cannot be moved, a supply pipe of the pump so arranged as to form a supporting abutment for the valve lock when it is engaged by the setting mechanism lock.

11. In combination, a measuring bowl, a delivery hose, a hose valve, a depending link from said valve, a locking member connected thereto, yielding means for maintaining said valve closed and the locking member inoperative, a measuring tube in said bowl, a rack adapted to operate said measuring tube, a gear for said rack, a setting shaft for said gear, a crank on said shaft, a setting dial having a plurality of apertures, a setting lever pivoted on said crank, a setting pin connected to said crank adapted to be inserted through an aperture in the crank and one of the coinciding apertures in the dial, a locking pin reciprocating through the gear supporting shaft connected to said setting lever, said setting locking pin and valve lock being adapted to interlock each other whereby when the setting pin is in the crank aperture and a dial aperture the locking pin is withdrawn from the path of the valve lock which is interposed in the locking pin's path so that the valve can open and when the setting pin is withdrawn from a dial aperture the locking pin will be interposed in the path of the valve lock and the valve cannot be opened.

12. In combination in a gasoline dispensing pump, a measuring bowl, measuring means for controlling the amount of fluid flowing from the bowl, a delivery hose, a valve therein, setting mechanism for the measuring mechanism comprising a rotating handle, a rocking handle mounted thereon, a setting pin carried thereby, a setting dial, said pin being adapted to be projected through an aperture in said rotating handle and an aperture in said dial, and means for adjusting the position of the aperture in said dial to calibrate the setting means with the bowl and its measuring means.

13. In a gasoline pump, a setting means comprising a numbered dial having a plurality of enlarged apertures, a movably-mounted reciprocating setting pin adapted to enter said dial apertures, jaw means positioned beneath said dial apertures adapted to exactly position said setting pin when it is so inserted in the apertures, and means of adjusting said jaw means with respect to said dial apertures whereby a fine adjustment of the position of the setting pin may be secured.

14. In combination, a setting drum, a dial having arcuate apertures therein, jaws pivoted beneath said apertures, adjusting screws adapted to position said jaws laterally with respect to said apertures to exactly position

a setting pin passing through the dial apertures.

15. In combination, a setting drum, a dial having arcuate apertures therein, jaws pivoted beneath said apertures, adjusting screws adapted to position said jaws laterally with respect to said apertures to exactly position a setting pin passing through the dial apertures, and means to lock said setting screw 10 in adjusted position.

16. In combination, a hose drain valve, setting mechanism, means to lock said valve closed when the setting mechanism is in inoperative position, means to lock the setting 15 mechanism when in set position while the valve is operated, supplementary operating means for said valve when the setting mechanism is in drain position, means suspended with the setting mechanism for unlocking a 20 supplementary valve locking means when in drain position, a drain back, a hose carrying the valve adapted to be inserted in the drain back means for locking the hose in the drain back connected to said supplementary valve 25 locking mechanism for opening said valve when the hose is locked in the drain back.

17. In combination, a hose, a valve therein, a link connected to said valve, a locking finger on the link, a drain back, a hose lock 30 on the drain back operating said link lock and said link for opening the valve when the lock is moved to locking position.

18. In combination, a measuring bowl, a reciprocating measuring tube, a hose, a valve 35 therein, a rack connected to the tube, a gear operating the rack connected to the tube, a crank operating the gear, a setting lever adapted to position the crank at varied measurements, a drain back for receiving the end 40 of the hose, a lock for locking the hose in the drain back, means interconnected between the valve and said lock for opening the valve when the hose is locked in the drain back, and means associated with the rack for unlocking 45 said locking means when the setting lever is set in drain position.

19. In combination, a measuring bowl, a reciprocating measuring tube, a hose, a valve therein, a rack connected to the tube, a gear 50 operating the rack connected to the tube, a crank operating the gear, a setting lever adapted to position the crank at varied measurements, a drain back for receiving the end 55 of the hose, a lock for locking the hose in the drain back, means interconnected between the valve and said lock for opening the valve when the hose is locked in the drain back, and means associated with the rack for unlocking 60 said locking means when the setting lever is set in drain position, and yielding means for restoring said locking means for locking the hose drain lock in inoperative position when the setting means is in other than drain position.

65 20. In combination, a measuring bowl, a re-

ciprocating measuring tube, a hose, a valve therein, a rack connected to the tube, a gear operating the rack connected to the tube, a crank operating the gear, a setting lever adapted to position the crank at varied measurements, a drain back for receiving the end 70 of the hose, a lock for locking the hose in the drain back, means interconnected between the valve and said lock for opening the valve when the hose is locked in the drain back, and means associated with the rack for unlocking said locking means when the setting lever is set in drain position, and yielding means for restoring said locking means for locking the 75 hose drain lock in inoperative position when the setting means is in other than drain position, and supplementary hose valve operating mechanism for use in other than drain position comprising means for locking the hose drain valve closed when the setting means is in inoperative position, and means for locking the setting means against movement when the valve is positioned for manual opening.

21. In combination in a gasoline dispensing pump, a drain back pipe, a collar thereon having a shoulder for receiving a shoulder hose and nozzle, a shouldered hose and nozzle adapted to be inserted therein, a swinging clamping lever for clamping said hose and drain back together, said lever having a locking eye, a locking lever adapted to be moved in a position to be locked to the swinging lever, a locking finger carried by the locking lever, a yielding stop for preventing the movement of said locking finger, a link connected to said finger, a drain valve in said hose adapted to be operated by the descent and setting mechanism adapted when in draining position to move said yielding stop out of the position of said locking finger to permit of the movement of the locking lever to locking position and the simultaneous opening of the hose valve.

22. In a gasoline dispensing pump, the combination of a main drain back pipe between the measuring bowl and the main source of supply, a branch for said pipe adapted to receive the free end of a hose draining the measuring bowl, a shouldered collar on the mouth of said branch, a shouldered nozzle on said hose engaging therewith, and therein, a swinging clamping lever adapted to engage the top of the hose collar, a locking eye on said lever, a locking lever adapted to be locked therewith, a shaft therefor journaled in an eye on said branch collar and an eye on the main drain back pipe, a locking finger on said shaft, a yielding stop engaging therewith and a setting rack adapted to depress said yielding stop, a bracket connected with said rack, and means for guiding said bracket and said rack.

23. In combination in a gasoline dispensing pump of a delivery tube comprising spaced pipes arranged substantially horizon-

- tally having their centers at a different elevation, an apertured connecting fitting for said pipes and a transparent pipe mounted therein, the bottom of which can be seen
5 through said aperture of the fitting whereby the bottom of the body of liquid flowing therethrough can be seen.
24. In combination, a fitting having apertured side walls oppositely disposed, a transparent pipe therein arranged substantially horizontally having its bottom above the bottom of the apertures whereby the bottom of the body of liquid flowing therethrough can be seen.
- 10 25. In combination, a fitting having apertured side walls oppositely disposed, a transparent pipe therein arranged substantially horizontally having its bottom above the bottom of the apertures whereby the bottom of the body of liquid flowing therethrough can be seen, and pipes communicating with said fitting and its transparent pipe having the centers thereof so arranged that they are off center with respect to one another.
- 15 20 25. In testimony whereof, I affix my signature.
25. In testimony whereof, I affix my signature.
EARL E. EICKMEYER.
